CLAIM

The ornamental design for an overlash cable roller, as shown and described.

DESCRIPTION

FIG. 1 is a frontal perspective view of an overlash cable roller.

FIG. 2 is a front view thereof;

FIG. 3 is a rear view thereof;

FIG. 4 is a left side view thereof;

FIG. 5 is a second view thereof;

FIG. 6 is a top view thereof; and,

FIG. 7 is a bottom view thereof.

The broken lines depict environmental subject matter that forms no part of the claimed design.

1 Claim, 5 Drawing Sheets
